EYEGLASS HOLDER

Janet Hauk Clark, Pasadena, Calif.

Application October 11, 1951, Serial No. 16,913

Term of patent 7 years

(Cl. D57—1)

To all whom it may concern:

Be it known that I, Janet H. Clark, a citizen of the United States, residing at 543 North Mentor Avenue, Pasadena, in the county of Los Angeles and State of California, have invented a new, original, and ornamental Design for an Eyeglass Holder, of which the following is a specification, reference being had to the accompanying drawing, forming part thereof.

Fig. 1 is a front elevational view of an eyeglass holder, showing my new design;

Fig. 2 is a central vertical sectional view taken on line 2—2 of Fig. 3; and

Fig. 3 is a front perspective view of the same.

I claim:

The ornamental design for an eyeglass holder, as shown.

JANET HAUK CLARK.
